A. WALKER

FENDER BRACE

Filed March 29, 1923

Inventor
A. Walker

By *A. Walker Jr.*
Attorney

UNITED STATES PATENT OFFICE.

ARCHIE WALKER, OF CEDAR GROVE, LOUISIANA.

FENDER BRACE.

Application filed March 29, 1923. Serial No. 628,479.

To all whom it may concern:

Be it known that I, ARCHIE WALKER, a citizen of the United States, residing at Cedar Grove, in the parish of Caddo and State of Louisiana, have invented certain new and useful Improvements in Fender Braces; and I do hereby declare the following to be a full, clear, and exact description of the invention, such as will enable others skilled in the art to which it appertains to make and use the same.

The invention has relation to means for stiffening and strengthening the wheel fenders of motor vehicles, whereby to prevent rattle and the bending thereof when subject to a relatively light blow or pressure.

The invention has for its object the provision of a brace which may be readily applied to either the front or the rear fender without necessitating any change in the construction of the brace, the latter being simple, easily applied to either the front or the rear wheel fenders, and efficient in either position.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application,

Figure 1 is a front view illustrative of the invention, the dotted lines indicating a license plate attached to the brace,

Figure 2 is a top plan view of the parts illustrated in Figure 1,

Figure 3 is a detail view of an end portion of the brace adapted for the rear fender; and

Figure 4 is a detail perspective view of the clip.

Corresponding and like parts are referred to in the following description and designated in the several views of the drawings by like reference characters.

The brace comprises a bar 1 of suitable length to connect opposite fenders. Oppo-

site end portions of the bar 1 are given a one-half twist, as indicated at 2, whereby to throw the ends of the bar in a plane at 55 a right angle to the plane of the bar. The ends of the bar are upwardly curved, as indicated at 3, to conform to the transverse curvature of the fenders, and the extremities terminate in hooks 4 to engage about the 60 outer edges of the fenders. An inclined portion 5 connects the curved end 3 with the twisted portion 2. The inclined portion 5 and the curved end portion 3 are disposed relatively at an obtuse angle, the latter being designated at 6. A bolt 7 passes through the angle 6 and through a clip applied to the lower side of the angle and serves as fastening means to secure the clip in the required adjusted position. The clip is of 70 angle formation to conform to the relative inclination of the parts 5 and 3 and comprises a long end 8 and a short end 9 upon opposite sides of the fastening 7. This clip is reversible so that either of its ends may 75 act jointly with the hooks 4, whereby to secure the brace to the fender. In practice, the front and rear wheel fenders are of different widths, the front fenders being somewhat narrower than the rear fenders, and 80 when the brace is adapted for the front fenders, as indicated in Figure 1, of the accompanying drawings, the clips are adjusted with the long ends 8 facing the hooks 4 and when the brace is adapted for the 85 rear fenders, the clip is adjusted so that the short end 9 faces the hook 4.

When the brace is in position, the hooks 4 engage the outer edges of the fenders, as indicated most clearly in Figures 1 and 3, 90 and the outer ends of the clips engage the inner edges of the fenders, thereby clamping the latter between the hooks and clips, the brace forming a tie between opposite fenders to prevent lateral movement thereof. As 95 indicated most clearly in Figure 1, a license plate 10 may be attached to and supported by means of the brace.

What is claimed is:

A fender brace consisting of a bar having 100 fender-engaging means adjacent one end thereof, a fender engaging clip to coact with said means, a fastening securing said clip to the bar for reversion end to end, said

clip being substantially V-shape in contour and disposed against the under surface of the bar, the portion of the bar engaged by the clip conforming in shape thereto to 5 overcome turning movement of the clip on said fastening when the brace is fastened in place, said clip being selectively engageable at each end with fenders, and said fas-

tening being disposed nearer one end of the clip than the other end of the clip. 10

In testimony whereof I affix my signature in presence of two witnesses.

ARCHEE WALKER.
